UNITED STATES PATENT OFFICE.

CHARLES M. HAESKE, OF SOUTH BEND, INDIANA.

DUMPING-WAGON.

No. 887,794.

Specification of Letters Patent.

Patented May 19, 1908.

Application filed March 30, 1907. Serial No. 365,476

To all whom it may concern:

Be it known that I, CHARLES M. HAESKE, citizen of the United States, residing at South Bend, in the county of St. Joseph and State of Indiana, have invented certain new and useful Improvements in Dump-Wagons, of which the following is a specification.

The present invention comprises certain new and useful improvements in dumping wagons, and the principal object of the invention is to provide mechanism for operating the hinged bottom sections so that the load may be rapidly or slowly dropped, and thereafter the said hinged bottom sections may be quickly returned to their closed position.

A further object resides in the arrangement and location of the operating mechanism whereby it will be in a position to be readily manipulated by a person upon the driver's seat of the vehicle, with the use of but one hand.

A further object resides in the arrangement of the operating mechanism whereby the opening and closing movements of the hinged bottom sections is controlled and regulated by means of one lever.

A further object is to provide means whereby the bottom sections will be caused to close one in advance of the other.

30 A further object is to provide a safety locking means for the operating mechanism which will normally hold the said operating mechanism in its locked position, but which can be readily disengaged therefrom when desired.

35 A still further object is to provide an improved form of hinge connection for the bottom sections that will cause them to swing clear of the sides of the wagon body, when they are in their lowered, or open position, 40 so that they will be out of the path of the material being dropped.

Other and further objects and advantages of the invention will be apparent from the following detailed description when taken in 45 connection with the accompanying drawings.

Of the accompanying drawings, in which like characters of reference refer to corresponding parts—Figure 1 is a longitudinal sectional view through a dumping wagon, 50 showing the arrangement of the lifting chain.

Fig. 2 is a front view of the mechanism for operating the lifting chain. Fig. 3 is side view of the operating mechanism the same being shown in its operative position in full lines 55 and in its inoperative position in dotted lines.

Fig. 4 is an end view of the wagon, the bottom sections being shown partly lowered. Figs. 5 and 6 are details of the hinge connection between the sideboards of the vehicle and the bottom sections. Fig. 7 is a detail 60 sectional view of one of the hollow sills of the bottom sections.

In the annexed drawings I have illustrated a conventional form of wagon body, the sides of which are extended forwardly and are 65 provided with bearings 10 for the drum, 11. As is shown more clearly in Fig. 2 of the drawings, this drum 11 extends entirely across the wagon, and is located below and forward of the driver's seat. An enlarged worm or 70 thread 12 is mounted upon one portion of the drum 11, preferably the left hand portion and is held relatively immovably thereto by means of bolts, or other securing means.

13—14 designate respectively the right 75 and left bottom sections which are hinged at their outer edges to the sides of the wagon body. One of these bottom sections (14) is provided with an extended portion 15, that forms an overlap for the opening formed by 80 the meeting edges of the two sections. The under faces of the two hinged bottom sections are each provided with a hollow sill 16—16 that extends the entire length of each section and is located at their meeting edges. Within 85 the upper portion of each of the sills 16—16, and at each end thereof, pulleys or rollers 17 are located.

Centrally located upon the rear face of the back of the wagon body are two pulleys 90 18—19. The pulley 19 is mounted to freely rotate upon its pivot, and the pulley 18 is so mounted that there is a resistance to its rotation. Any preferable means may be used to cause this resistance to the rotation of the 95 pulley 18, the simplest being the present structure in which the resistance is caused by the increase in the size of its pivot.

20 designates a chain one end of which is securely attached to the right hand side of 100 the drum 11, and has a few turns wound upon that portion of the drum. The loose portion of the chain is then passed over a pulley *a* carried by the front of the wagon body and then down and through the sill of 105 the bottom section 13, up over the two back pulleys 18—19, thence into and through the sill of the section 14, up and over the pulley *b* at the front of the wagon body, and thence to the drum 11, where it is wound upon the 110

enlarged worm or thread 12, after which its end is securely attached to the drum adjacent to or upon the said worm or thread.

5 A ratchet or pinion 21 is rigidly mounted upon the drum 11, at the extreme right hand side.

10 22 designates an elongated lever, the lower portion of which is bifurcated to provide the arms 23—23, and these arms terminate in the circular portions 24—24, which are of a size sufficient in diameter to permit of the drum 11 being readily passed therethrough.

15 25 designates a pawl that is pivoted within the upper part of the bifurcated portion of the lever 22. A rod 26 has its lower end in pivotal engagement with the pawl 25, and its upper end is in pivotal engagement with a hand lever 27 which is in turn pivotally connected with the upper end of the lever 22.

20 28 designates a lever that is located to the left of lever 22, and this lever 28 extends forward adjacent to the bifurcated portion of said lever 22. The lower end is bent around the circular portion 24 one of the bifurcated 25 arms of lever 22, and then extends forward a short distance, and is then bent around to form a loop portion 29, that terminates directly in front of the ratchet or pinion 21.

30 30 designates a bracket that extends from the side of the wagon body, and has its end bent around the side of the loop 29.

35 31 designates a pivot bolt that extends through the end of bracket 30, and the loop 29, and has bearing in the side of the wagon body.

32 designates a pawl that is pivotally mounted in the end of the loop 29, in proximity to the ratchet or pinion 21.

33 designates a locking jaw or hook that is 40 pivoted to one side of the lever 28. The curved lower portion of this hook or jaw is of substantially the same contour as the drum 11, and is so located upon the lever 28, that when it is dropped down, its hook portion 45 will engage with the drum 11.

50 The relative arrangement and location of the parts just described is best shown in Figs. 2 and 3 of the drawings, and by reference to said figures it will be seen that the bifurcated portion of lever 22, extends down upon both sides of the ratchet or pinion 21, and that the circular end portions through which the drum passes rests against the ends of the hubs of the said ratchet or pinion. The pawl 55 25 which is mounted in the bifurcated portion is so arranged that its ratchet-engaging end extends rearwardly and when in engagement with the ratchet or pinion, such engagement is with the rear portion, which prevents 60 the said ratchet or pinion from rotating forwardly. The pawl 32 that is mounted in the loop 29 of lever 28, has its ratchet-engaging end so arranged that it extends rearwardly, and is normally in engagement with the front 65 of the ratchet or pinion, which also prevents

said ratchet or pinion from rotating forwardly, or in a direction to cause the opening of the bottom sections.

In dumping wagons of this general type, one disadvantage has resided in the fact that 70 when the hinged bottom sections are in their dropped or open position, they do not swing far enough outside of the line of the side boards of the wagon body, the result being that there are projecting edges left in the 75 path of the material being dropped, and as such edges catch a considerable amount of the material, difficulty is caused when it is attempted to return the bottom sections to their closed position. With a view of obviating this objection, I have designed the form of hinge connection shown more clearly in Figs. 4, 5 and 6 of the drawings, in which 80 34 designates metal straps that are secured to the under sides of the bottom sections. 85 These straps extend to the outer edges of the bottom sections, and their end portions are bent first at right angles to form a short upward extension, and the end of this extension is then bent over upon itself to form an eye 90 35. The side boards are each provided with vertically arranged metal straps 36, the lower ends of which are each provided with the enlarged portion 37, provided with an opening. Preferably the periphery of this enlarged portion is slightly concaved to form a seat for a 95 U-bolt 370, that forms an additional securing means for the straps 36 and also forms a strengthening means for the enlarged portions 37. In assembling the hinges the bolt 100 100 or pintle is placed within the eye 35 with its ends projecting from each side thereof. The side straps 36 are then placed in position so that the ends of the bolt or pintle will be within the openings or recesses in said enlarged portions, after which said side straps are secured in position on the side boards of the wagon body.

105 The operation of the invention is as follows:—Assuming the wagon to be in its closed position, and that it is desired to open the bottom sections.—The locking jaw 33 is turned upon its pivot, freeing it from engagement with the drum 11. Lever 28 is then free to be thrown forward. Such forward movement of lever 28 released pawl 32 from its engagement with the ratchet or pinion 21. The pawl 25, by means of its rod and hand lever engagement with lever 22, is then thrown out of engagement with the ratchet or pinion 21, the drum 11 is then free to revolve. The weight of the load causes the hinged bottom sections to drop which of course carries with them the chain 20 that is wound upon the two portions of the drum 11, and as said drum is free to revolve, there will be nothing to interfere with the chain running freely through both sills 16 until said bottom sections have reached their lowest 125 position. When such bottom sections are 130

at their lowest position, they will, by means of the peculiar form of hinge connections with the sideboards, be caused to swing out beyond the line of the sideboards of the wagon body, and consequently out of the path of the material to be dropped. It will be understood that the degree of speed at which the bottom sections may be lowered is controlled by means of the pawl 25. For instance, if a slow dump is desired, the pawl 25 is not fully released from the ratchet or pinion, but is allowed to "click" along the teeth thereof, the degree of pressure, or resistance, afforded by said pawl being regulated by the amount of pressure exerted upon the hand lever 27.

When it is desired to close the bottom sections, lever 28 is thrown back to its rear position, and the locking jaw 33 is turned upon its pivot and allowed to fall to its lowered position where its curved end engages with drum 11. The locking pawl 32 having been brought into engagement by the backward movement of lever 28, the said pawl is in position to prevent a forward rotation of the ratchet or pinion, or a rotation that would permit of further opening of the hinged bottom sections. As the lower ends of the bifurcated portion of lever 22 are loosely mounted on the drum 11, such lever can be moved backward and forward relatively to said drum. Lever 22 is then rocked forwardly and rearwardly, the forward movement causing the pawl 25 to "click" along the ratchet or pinion 21, the rearward movement causing the pawl to engage with and rotate said ratchet or pinion. The rotation of the ratchet or pinion imparts its rotations to the drum 11. As the ends of the chain 20 are attached to different portions of the drum 21, and such different portions of the drum are of different diameters, it will be readily understood that the chain is wound upon the drum at different speeds—that is, the end secured to the larger portion of the drum is wound faster than the portion of the chain which is wound upon the portion of the drum that is of a small diameter. It will also be understood that when the bottom sections are in their opened or lowered position the chain will be hanging practically loose—that is, there will be no pulling pressure upon it. And it will be further understood that when the chain is in such loose position, it will practically form two long loops—one extending down the right side of the wagon from the front pulley *a* down and through the sill and up to the two pulleys 18—19 at the rear of the wagon body. The other loop extends from the pulleys 18—19 down into and through the sill 16 at the left side of the wagon body then up to the pulley *b* at the front of the wagon body. As the drum 11 is rotated to wind the chain 20 thereon, the first or initial lifting movement will be

imparted to the left hand loop, for the reason that, as the chain is practically loose in both loops, the first movement of the chain is one that will tighten it, and when the chain is tightened, there is a slight resistance to the further movement of the right loop caused by the retarding action of friction pulley 18, such retarding action, while being slight, is sufficient to enable the left loop to have started the lifting movement of section 14, and as the retarding action of the pulley 18 is continuous, and as the left loop is being drawn faster than the right loop on account of its being wound upon the enlarged portion of the drum 11, the result is that the bottom section 14 is closed in advance of the bottom section 13. And as bottom section 14 carries the overlapping portion 15, it will be in position to cover the opening formed by the meeting edges of the two sections.

From the foregoing description it is thought the objects and advantages of the invention will be apparent. It will be understood that while I have described the locking jaw 33 as a means for retaining the lever 28 in position during the raising of the bottom sections, said locking jaw performs the further function of providing an efficient means for retaining such locking lever in position when the wagon is traveling, it being of especial advantage as when the wagon is traveling over rough roads where there is a liability of the levers being jolted out of position. It will also be understood that any suitable means may be provided to prevent the chain from being displaced from its carrying pulleys. For example, I have provided the sill pulleys with a loop through which the chain passes, and have provided the rear pulleys with a sheath or covering, and have mounted the front pulleys in brackets.

Throughout the specification and in the drawings I have set forth the lifting means as an endless chain. This has been done for convenience and as the preferred form, but I wish it to be understood that I do not desire to limit myself to a chain, for it will be obvious that any other form of cable possessing the necessary strength may be substituted for the chain.

I claim as my invention:—

1. A dumping wagon comprising a body, bottom sections hinged thereto and having their free edges each provided with a hollow sill, one of said sills being provided with an overlapping portion, a chain having portions passed through each sill, a drum to which said chain is connected, one portion of said drum being of increased diameter, the ends of said chain being connected to different portions of said drum, and means for retarding said drum.

2. A dumping wagon comprising a body, bottom sections hinged thereto, and having

their free edges each provided with a hollow sill, one of said sills being provided with an overlapping portion, a chain having portions passed through each sill, a drum to 5 which said chain is secured, and means for retarding the movement of said sections, said sections being mounted to swing beyond the plane of the said body when in dumping position.

10 3. A dumping wagon comprising a body, dumping sections hinged thereto, a drum connected with said sections, a ratchet on said drum, a lever for rotating the same, a locking lever having a pawl engaging said 15 ratchet, and a locking member depending from said locking lever and normally engaging said drum.

4. A dumping wagon comprising a body, dumping sections hinged thereto, a drum connected with said sections, a ratchet on said 20 drum, a lever for rotating the same, a locking lever having a pawl engaging said ratchet,

and a locking member depending from said locking lever and provided with a curved portion normally embracing the lower face of 25 said drum.

5. A dumping wagon comprising a body, dumping sections hinged thereto, a drum connected with said sections, a bifurcated ratchet lever mounted on said drum, a ratchet 30 wheel secured to said drum and located between said bifurcated portions of said lever, a pawl mounted on said lever and engaging said ratchet wheel, a locking lever also having a pawl engaging said ratchet, and a locking member depending from the latter lever and embracing the lower face of said drum. 35

In testimony whereof I affix my signature, in presence of two witnesses.

CHARLES M HAESKE.
